UNITED STATES PATENT OFFICE.

HENRY WACHTER, OF COLUMBUS, OHIO.

GAME-BOARD.

SPECIFICATION forming part of Letters Patent No. 447,851, dated March 10, 1891.

Application filed August 25, 1890. Serial No. 362,991. (No model.)

To all whom it may concern:

Be it known that I, HENRY WACHTER, a citizen of the United States, residing at Columbus, in the county of Franklin and State 5 of Ohio, have invented a certain new and useful Improvement in Games, of which the following is a specification.

My invention relates to the improvement of house games.

10 The objects of my invention are to provide an improved form of game-board of such construction and arrangement as to admit of three separate games being played thereon, to so construct and arrange the same as to 15 admit of the game of base-ball being played thereon and the making from said game of a complete score, such as is usually used as a record of the outdoor game of ball, to provide improved means for giving impetus to 20 the ball, and to provide improved stops and deflectors. These objects I accomplish in the manner illustrated in the accompanying drawings, in which—

Figure 1 is a plan view of my improved 25 game-board. Fig. 2 is a view in perspective of the ball pitching or shooting apparatus. Fig. 3 is a vertical longitudinal section of the ball-receptacle or pitcher's box. Fig. 4 is a view in perspective of the ball-deflecting 30 plate. Fig. 5 is a view in perspective of one of the stop-pieces. Fig. 6 is a transverse section on line $\alpha\alpha$ of Fig. 1, and Fig. 7 is a side elevation of a pin employed in indicating the 35 positions of the players in base-ball.

Similar letters refer to similar parts throughout the several views.

a represents an oblong board, having its edges flanged upwardly, and having its forward end curved in the arc of a circle, as 40 shown. This board may have its head so elevated as to cause an incline toward its rear end, if desired, to facilitate the movement of the ball thereon. Formed on the upper face of the board in its forward portion is an out- 45 line or representation of the base-ball diamond or infield, which consists of a home plate or base, (indicated by Fig. 4,) and in concave depressions or seats b at the remaining corners of the diamond, which indicate 50 the first, second, and third bases, and which, as shown, are numbered 1, 2, and 3, respectively. Formed in the board a near each of

the depressions b is a pin-hole, which is adapted to receive and support a suitable peg b' or t , for the purpose hereinafter described. 55

Supported in the center of the diamond, at the point usually occupied by the pitcher, is a short horizontal tube c , said tube being pivotally connected with the board a by means of a pivot or swivel-screw c' , which, being 60 rigidly connected with the tube c , enters a suitable socket or screw-hole in said board. The rear end of this tube is, as shown, provided with one or more inwardly-projecting lugs c^2 , which are adapted to prevent the ball 65 c^3 , which is normally supported within said tube, from escaping through the rear end thereof.

f represents a ball-delivering device, which consists of a metal spring-strip doubled at its 70 central portion to form two spring-arms or finger-pieces, which, running approximately parallel to about the center of their length, are made to diverge toward their outer ends by outward curves. The tension of these 75 spring-fingers is regulated by an adjusting-screw f' , which passes through and connects the approximately parallel portions of said spring-arms and has one of its ends secured to one of said arms and passes loosely through 80 the remaining arm. The distance between these spring-arms is regulated by a nut f^2 upon the free end portion of the adjusting-screw f' , said nut being made to abut against one of said spring-arms, as shown. 85

Supported upon the face of the board, to which it is glued or otherwise secured, immediately in rear of home-plate, is an angular or V-shaped deflecting plate or projection g , which is preferably formed of rubber. Formed 90 in the board-face on opposite sides of the second base and without the infield diamond are the ball depressions or seats $g' g^2$, which are numbered, respectively, 5 and 6.

$h h'$ represent, respectively, ball depressions corresponding with the depressions g , which are located in the rear and outer side of the depressions g' and g^2 , while between said depressions $h h'$ and in rear thereof is a similar depression h^3 . In rear of the depression h^3 are arranged in a transverse row three depressions $h^4 h^5 h^6$. 95 100

i represents a bell, which is secured in any suitable manner to the face of the board in

rear of the three last-described depressions, said bell being partially surrounded on its rear side with a semicircular projection *k*, which may be of rubber or other desirable material. The circle of which said projection *k* forms a part is continued on the forward side of the bell by projecting lugs *k'*, of rubber, which are triangular in cross-section, said lugs or projections being ar-

5 10 ranged at such distance one from the other as to prevent the entrance between them of the ball *c*³. A space *l* is left, however, in said circle in the forward side thereof of such size as to admit said ball.

15 15 On opposite sides of the circular inclosure I preferably provide the board-face with ball depressions *j j'*, while similar depressions *m m'* are formed in the lower portion of said board.

20 20 The depressions indicated by the letters *h* *h*³ *h*⁴ *h*⁵ *h*⁶ *j j'* *m m'* are numbered, respectively, 7 8 9 10 11 12 13 14 15 16. The spaces between the rubber stops *k'* are numbered consecutively from 17 to 22. The lower or 25 rear end of the board has its corners partitioned off to form bevels by diagonal partitions *n*, the ends of which meet the side and rear end flanges at equidistant points from the board-corners.

30 30 *n'* represents rubber lugs or projections, which are secured to the board-face at equidistant points at the rear ends of the partitions *n*, and extend forwardly from the rear end flange of the board. The spaces between 35 these projections *n'* and the spaces between the said projections and the partitions *n* are each adapted to receive the ball *c*³, said spaces being numbered consecutively from 23 to 28.

In constructing my improved board I cause 40 to be printed in front of the deflecting-plate *g* the words "Error by catcher, 1 B.," indicating that an error by the catcher will entitle the batter to take a base. At first base appear the words "Fly out by 1 B.," at third 45 base "Fly out by 3 B.," and at second base the words "Double play." Placed near each of the remaining depressions are similar terms, which indicate the result of the play, and in case a hit, error, put-out, or assist is indicated 50 the movement to which the player is entitled is also indicated.

p represents short upwardly-projecting rubber lugs corresponding with the lugs *k'*, said lugs *p* being arranged in groups of two or 55 more in rear of the ball depressions, and so set as to form a stop or pocket for the reception and retention of the ball *c*³. Adjoining the pockets thus formed the result of the play is indicated in case the ball should be 60 caught in one of said pockets, and each of said pockets is also indicated by a number.

p' represent deflecting-lugs, which correspond with lugs *p* and *k'*, and may be arranged at desired points on the board for the 65 purpose of deflecting the ball during its rearward course. The spaces between each of the lugs *k'* are provided with lettering, indicat-

ing the result of the play in case the ball is caught between any two of said lugs. The space between the bell *i* and the circle formed by the curved projection *k* and lugs *k'*, which surround said bell, is marked with the words "Home run." Each of the spaces between the projections *n'* and *k'* is lettered to indicate the result of the play in case the ball should lodge therein.

The manner of playing a game of base ball on my improved board may be illustrated as follows: Each of the two players having selected pegs *b*² of the desired color, the player 80 who is out proceeds to deliver the ball from the pitcher's box *c* to the player who is in, which is accomplished by clamping that portion of the periphery or ball surface which projects through the rear end of the tube *c* between the spring-fingers *f* of the impelling device. By pressing the spring-arms of this device toward each other the ball is driven forward through the tube *c*, its release and momentum being gained through the friction 90 of the ends of the impelling device as they slip from the rounded surface of the ball. The ball, traveling forward, comes into contact with the deflector *g* and is turned to the right or left thereby. We will suppose that the 95 ball after leaving the deflector travels down the board and enters the depression marked *g'*. As indicated by the lettering adjoining these depressions, one base hit is thus made, which entitles the batter to take first base 100 and entitles a base runner, if any there be, to move up two bases. This running or moving up on bases is accomplished by moving the pegs *b*², which represent the players, from the peg-socket of one base to that of another. 105 The first batter having thus placed his peg at first base, his opponent proceeds to deliver the ball for the second batter. We will suppose that the ball of the second batter enters the circle marked "Home run" and rings the 110 bell *i* by contact therewith. In this case the batter is given credit for a home run. If the ball after leaving the tube *c* should return and lodge therein, the batter is out and the 115 "put-out" is credited to the pitcher, as indicated by the lettering, and in case the ball is caught in the angle of the deflecting-plate an error is given the catcher. Owing to the fact that the ball-receiving depressions which are 120 formed in the board correspond in position with the positions of the players in the outdoor game of ball and the fact that all the points at which the ball may lodge or rest are so lettered or numbered as to indicate the result of the play and its effect on the batter or 125 runner, it will be seen that a score may be kept of the game which will conform to the score of the ordinary base-ball game, and that the rules which apply to the outdoor game may be applied to the house game. By the use of the ball delivering or impelling device *f* it is obvious that the movement of the ball after it leaves the tube *c* may be greatly affected by the twist imparted to the ball by

said impelling device, this twist varying with the manner in which the impelling device is held and the ball grasped.

The manner of playing a game of "odd and even" on my improved board is substantially as follows: Any number of persons from two to eight may play, and any number of points which may be decided upon may constitute a game. Each player before beginning selects 10 one of eight differently-colored pins or small pegs *s* and retains said peg and color throughout the game. *t* represents a peg, which has its enlarged head provided with a number of pin-sockets, as shown. One of these pegs *t* is inserted in each of the peg-sockets at the bases. The ball is impelled in the same manner as described for playing of base ball, and in case it lights or rests in a depression or pocket bearing an even number the player is 15 entitled to place his pin *s* in one of the pin-sockets of the first-base peg *t*. He again shoots, and in case the ball again lodges at a point indicated by an even number he is entitled to move his pin from the first to the 20 second base peg, this play and movement of the pin being repeated so long as the ball shall lodge at an even number. Having passed first, second, and third bases, the player has 25 scored one point. In case the ball lodges at a point indicated by an odd number, or where no number appears, he is entitled to no move of the pin and must give way to the next player.

In playing the game of bagatelle the player 30 is, as is usual in this game, given credit for the number of points made, the points being calculated from the number of the depression or pocket which catches the ball.

From the construction and arrangement 35 herein described it will be seen that the three games mentioned may be played upon one

board, and that the game of base ball may be played with such near resemblance to the outdoor game as to create intense interest therein.

45

I am aware that game-boards have been produced heretofore in which a ball-impelling device, ball depressions, and stop and deflecting pins have been used, and therefore do not claim, broadly, such constructions. 50

Having now fully described my invention, what I claim, and desire to secure by Letters Patent, is—

1. In a game, the combination, with a flanged game-board having numbered and lettered ball depressions formed therein, a ball-supporting tube *c*, supported upon said board, and a V-shaped deflecting-plate projecting from said board in front of said tube, of a ball-impelling device consisting of the bent 60 or double spring-strip *f*, the arms of which are connected by an adjusting-screw *f'*, substantially as and for the purpose specified.

2. In a game, the combination, with a flanged board *a*, the representation of a base-ball diamond thereon, numbered and lettered ball depressions *b*, located at the side and lower corners of said diamond, similar depressions arranged in rear of said diamond, peg-sockets adjacent to each of said depressions *b*, 70 tube *c*, supported in the center of said diamond and provided with end stop-lugs *c'*, a ball normally supported within said tube, and a ball-impelling device consisting, as described, of the doubled spring-strip *f* and an 75 adjusting-screw *f'*, connecting, as described, the arms of said spring-strip, substantially as specified.

HENRY WACHTER.

In presence of—

BARTON GRIFFITH,
FRANK WHITNEY.
